CLAIM

The ornamental design for an inflatable aircraft bed with carrying case and vacuum bag, as shown and described.

DESCRIPTION

FIG. 1 is an exploded isometric top view of the inflatable aircraft bed with carrying case and vacuum bag.

FIG. 2 is an exploded front view thereof.

FIG. 3 is an exploded back view thereof.

FIG. 4 is an exploded side view thereof.

FIG. 5 is an exploded side view thereof.

FIG. 6 is an exploded top view thereof; and,

FIG. 7 is an exploded bottom view thereof.

The broken lines in the drawings are for the purpose of illustrating portions of the inflatable aircraft bed with carrying case and vacuum bag that form no part of the claimed design.

1 Claim, 6 Drawing Sheets
